UNITED STATES PATENT OFFICE.

JOSEP LEWANDOWFSKI, OF ALLEGHENY, PENNSYLVANIA.

CURTAIN-FIXTURE.

SPECIFICATION forming part of Letters Patent No. 728,120, dated May 12, 1903.

Application filed February 20, 1903. Serial No. 144,177. (No model.)

To all whom it may concern:

Be it known that I, JOSEP LEWANDOWFSKI, a citizen of the United States of America, residing at Allegheny, in the county of Allegheny and State of Pennsylvania, have invented certain new and useful Improvements in Curtain-Fixtures, of which the following is a specification, reference being had therein to the accompanying drawings.

10 This invention relates to certain new and useful improvements in curtain-fixtures, and has for its primary object the provision of novel and effective means for the securing of curtains to the supporting-pole without the aid of the ordinary rings and pins.

Briefly described, my invention consists in providing an attachment to be applied to the ordinary curtain-poles, which attachment carries a supplemental pole or binding-rod 20 adapted to be forced toward the supporting-pole and bind the curtain firmly against the latter.

The device or attachment in its construction embodies an open link or frame which receives the supporting-pole of the curtain. The curtain is adapted to be wrapped over the supporting-pole, and the open link or frame receives a supplemental pole or binding-rod, which supplemental pole or binding-rod is moved by means of a lever against the curtain and binds same against the supporting-pole. The actuating-lever is held in the closed position by means of a pawl, which engages with teeth on the open link or frame.

35 Means may be provided, such as cords, attached to the device and extending downward to a position where they may be easily engaged and operated, whereby to release the device and permit the disengagement of the curtain, if desired.

All of the above construction, together with other details entering into my invention, will be hereinafter more specifically described, and then particularly pointed out in 45 the appended claims, and in describing the invention in detail reference will be had to the accompanying drawings, forming a part of this application, and wherein like numerals of reference will be employed to designate 50 like parts throughout the different views of the drawings, in which—

Figure 1 is a front view of the attachment

detached from the pole. Fig. 2 is a side elevation of the same. Fig. 3 is a plan view showing the attachment in position on the 55 curtain-pole; and Fig. 4 is a cross-sectional view through the pole, showing the attachment in the closed position for holding the curtain.

As stated, my device comprises an attachment to be placed on the curtain-pole and which carries a supplemental pole or binding-rod to engage the curtain. One or more of the devices may be mounted on the curtain-pole, and in the accompanying illustration I 65 have shown two of the same in position, one near each end of the pole. However, a single device may be employed, though in practice I prefer two or more, as by the employment of two, one near each end of the pole, I 70 am enabled to better support the supplemental pole or binding-rod.

The device or attachment comprises an open link or frame 1, the opening in which is somewhat curved and larger at one end than 75 at the other. In the enlarged end 2 of this opening the curtain-pole 3 is received. In the contracted portion 4 of the slot or opening the supplemental pole or binding-rod 5 is received. The curtain 6 is bound firmly 80 between these two poles, as will later be described. The frame or open link has pivoted thereto a lever 7. This lever 7 carries a hook end 8, which engages with the binding-rod or pole 5 when the lever is forced rearwardly or downwardly and forces the binding-rod or pole 5 up against the curtain 6. The lever carries an ear or lug 9, to which is pivoted a pawl 10, adapted to engage with 85 teeth 11 on the periphery of the frame or link 1. This pawl is normally held in engagement with said teeth by means of a spring 12, attached at its one end to the frame or link and at its other end to the pawl. A catch 14 is provided on the pawl for convenience in lifting the same to disengage from the teeth 11. I may, if desired, provide the pawl with an eye 15 and to the front end of the frame or open link 1 attach a bracket 16, provided in its upper end with a roller 17. Attached 90 to the eye 15 is a cord 18, which is passed over the roller 17 and led down to a suitable point, where it may be easily engaged. When a pull is made on this cord, the pawl

10 will be raised, and the action of the spring 12 pulling the pawl forward draws the lever 7 forward, allowing the hook end of the lever to recede from the binding-rod and permitting the latter to move back in its slot whereby to loosen the curtain. For pulling the lever backward or downward to tighten the binding-rod 5 I may attach a cord 19 to said lever. The attachment is shown in position 10 on the pole with the lever projecting rearwardly. It will be evident, however, that it may be placed upon the pole in any desired manner. The pole is supported in the ordinary brackets 20. To secure the curtain, the 15 latter is merely passed over the curtain-pole and the lever then actuated to force the binding-rod up against the curtain and bind the same against the pole, as seen in Fig. 4.

If desired, I may employ set-screws 21 for 20 fastening the device to the pole 5, though generally I have found that the same remains in position without such fastening means.

While I have shown and described the device in detail as it is practiced by me, yet it 25 will be evident that various slight changes may be made in the details of construction without departing from the general spirit of my invention.

Having fully described my invention, what 30 I claim as new, and desire to secure by Letters Patent, is—

1. In combination with a curtain-pole, a securing device for the curtain comprising an open link or frame, a binding-rod carried 35 thereby and movable in the link or frame, a pivoted lever carried by the frame and provided with a hook end to engage and actuate the binding-rod, and a spring-held pawl car-

ried by the lever and engaging the link or frame to hold the lever in the locked position, 40 substantially as described.

2. In combination with a curtain-pole, a securing device mounted thereon for binding the curtain thereto and comprising an open link or frame, a pivoted lever carried thereby and engaging a binding-rod mounted in the link or frame, and means carried by the lever and engaging the link or frame for holding the lever in the closed position, substantially as described. 45

3. In combination with a curtain-pole, a securing device for the curtain mounted on the pole and comprising an open link or frame, a lever pivoted to the frame, a binding-rod mounted in the link or frame and engaged by 50 said lever, and means for locking the lever in the closed position to hold the binding-rod against the curtain and bind the latter between the rod and the pole, substantially as described. 55

4. In combination with a curtain-pole, a securing device for fastening the curtain thereto and comprising an open link or frame, a pivoted lever carried by said frame, a binding-rod mounted in the frame and engaged 60 by said lever, a pawl carried by the lever, and a spring for holding said pawl in engagement with the frame to secure the lever in the locked position, substantially as described. 65

In testimony whereof I affix my signature 70 in the presence of two witnesses.

JOSEP LEWANDOWFSKI.
